DESIGN FOR A RING MOUNTING

Jacob H. Schaeffer, Brooklyn, N. Y., assignor to Shiman Bros. & Co., Inc., New York, N. Y., a corporation of New York

Application March 2, 1938, Serial No. 75,520

Term of patent 3½ years

To all whom it may concern:

Be it known that I, Jacob H. Schaeffer, a citizen of the United States and resident of New York city, (Borough of Brooklyn), in the county of Kings and State of New York, have invented a new, original, and ornamental Design for a Ring Mounting, of which the following is a specification, reference being had to the accompanying drawing, forming a part thereof, and of which Figure 1 is a view in side elevation, Fig. 2 is a top plan view, Fig. 3 is a view in end elevation, Fig. 4 is a sectional view on the broken line 4—4 of Fig. 2, and Fig. 5 is a sectional view on the line 5—5 of Fig. 1, showing my new design for a ring mounting.

I claim:

The ornamental design for a ring mounting substantially as shown.

JACOB H. SCHAEFFER.
